WESTERN ELECTRIC COMPANY, INCORPORATED, OF NEW YORK, N. Y., A CORPORATION OF NEW YORK

STRAND REELING APPARATUS

Application filed July 31, 1926. Serial No. 126,151.

This invention relates to strand reeling apparatus, and has for its principal object the provision of simple and efficient mechanism for constantly maintaining a strand being 5 reeled under a substantially uniform tension.

In accordance with the general features of the invention, there is provided, in one embodiment thereof, a vertically mounted take-up spool which is driven through the engagement of frictional plate members placed underneath the spool head. A spiral spring interconnecting the driving means and the driving frictional plate member serves to constantly maintain the strand being reeled 15 under a substantially uniform tension.

Other features and advantages of the invention will become apparent in the following detailed description, reference being had to the accompanying drawings, wherein

20 Fig. 1 is a fragmentary elevational view, partly in section, of a tinsel serving apparatus embodying the features of the present invention;

Fig. 2 is an enlarged vertical section of the 25 improved strand reeling apparatus, and

Fig. 3 is a detail section taken on line 3—3 of Fig. 2.

The present invention may be employed to advantage in conjunction with a multiple 30 unit strand or tinsel serving apparatus wherein the take-up spools are served by distributors which are operated by a common driving source. It should be understood, however, that the invention is not limited to such use, but is capable of various other applications within the scope of the appended 35 claims.

Referring now to the drawings in detail, and particularly to Fig. 1 thereof, the numeral 10 indicates a main supporting frame 40 of a multiple unit tinsel serving apparatus of which each individual unit comprises a strand supply 11, a serving head 12, a capstan 13, and a take-up spool 14. Inasmuch as each 45 of the individual units are similar in construction and operation, a description of one of the units is believed to be sufficient.

Rotatably journaled in the frame 10 is a vertically disposed main drive shaft 15 which 50 is constantly driven from any suitable source

of power (not shown). Secured to the shaft 15 is a gear 17, which, through an intermediate gear 18, drives a pinion 19 secured to a vertical disposed shaft 20. A shaft 21 disposed in axial alignment with the shaft 20 is driven therefrom by means of a suitable clutch 22 actuated by a hand lever 23. The shaft 21, in turn, drives a vertically disposed hollow spindle 25 through a gear 26 and a pinion 27 secured to the shaft 21 and spindle 25, respectively.

The serving head 12 is mounted upon the spindle 25 so as to be rotatable therewith and may be of the type illustrated and described in the copending application of G. A. Bouvier, Serial No. 699,441, filed March 15, 1924, now Patent No. 1,614,596, issued January 18, 1927. Carried by the serving head is a guide pulley 29 over which a cotton core 28 is withdrawn by the capstan 13 from the supply spool 11. The capstan 13 is driven from a vertically disposed shaft 30 through gears 31 and 32, the shaft 30 being driven from the shaft 21 through gears 33 and 34 secured to the shafts 21 and 30, respectively.

Rotatably supported upon the spindle 25 are spools 36 and 37 from which tinsel strands 38 and 39, respectively, are drawn and superimposed upon the cotton core 28 in a manner fully described in the above mentioned copending application. The composite conductor passes over a guide pulley 40 to an idler roller 42 associated with the capstan 13. After passing several turns around the capstan 13 and roller 42, the composite conductor passes over a distributing pulley 44 which serves it upon the take-up spool 14. The distributing pulley 44 is carried at one end to an arm 46, which arm is secured at its opposite end to a horizontally disposed shaft 48. The shaft 48 is reciprocated or rocked by a horizontal face cam 49 engaging rollers 50 and 51 carried by a bifurcated end portion 52 of the shaft, the cam 49 being secured to the shaft 15. For a more detailed description of this construction reference may be had to a copending application of J. N. Selvig, filed July 31, 1926, Ser. No. 126,153, now Patent No. 1,673,887, issued June 19, 1928.

100

The take-up spool 14 is driven from the shaft 30, which shaft extends upwardly through a housing 45 supported by the frame 10. It should be understood that the serving head 12, capstan 13 and take-up spool 14 are all driven from the shaft 20 through the clutch 22, one of which clutches being provided in each unit, whereas the distributors of each and all of the units are operated together from the drive shaft 15.

The apparatus thus far described does not in itself constitute a part of the present invention but is being disclosed in this application for the sake of clearly illustrating a specific embodiment of the invention.

The construction and operation of the take-up mechanism which constitutes the subject matter of the present invention will now be described. As shown in Fig. 2, the shaft 30 has formed, at its upper end, a pinion 54 which meshes with an internal gear 55 formed in a circular disk 56. The disk 56 is provided with a hub portion 57 which is free to rotate about a vertically disposed sleeve 59 rigidly supported in the housing 45. Rotatably mounted within the sleeve 59 is a vertically disposed spindle 60 to which is secured an inverted cup shaped member 62. A reduced portion 63 of the spindle 60 extends upwardly beyond the member 62 and is adapted to receive the take-up spool 14 which is secured to the member 62 so as to be rotatable therewith by means of a pin 64 fastened to the member 62 and engaging an aperture formed in the head of the spool.

Encircling a raised portion 65 formed on the under side of the member 62 is an annular friction pad 66, the bottom side of which engages a circular disk 67. The disk 67 is rotatably supported upon an annular flange 68 formed at the upper end of the sleeve 59, a plurality of friction reducing ball bearings 70-70 being provided to cause the disk 67 to rotate freely. Interconnecting the disk 67 and the disk 56 is a spiral spring 72, the outer end of which is fastened to a pin 73 secured to the disk 56 while its inner end is fastened to a pin 74 secured to the disk 67. Due to this construction, it is obvious that rotation of the disk 56 in a clockwise direction (Fig. 3) causes a winding of the spring 72, since the disk 67 tends to remain stationary due to the weight of the member 62 and the take-up spool 14. This winding of the spring is limited, however, by a pin 75 fastened to the disk 67 and positioned so as to be engaged by the pin 73 after a predetermined amount of tension has been introduced in the spring. The pin 75 may be readily secured in either of a plurality of apertures 76 provided in the disk 67, in accordance with the amount of tension which may be found suitable to maintain in the spring 72 during the operation of the apparatus, which, obviously, depends upon the tension of the strand being reeled.

When operating the above described apparatus, the shaft 15 is constantly driven, and thus, the distributors of all of the units are continuously in motion. By operating a clutch 22, one of which is provided in each unit, the serving head, capstan and take-up spool of any particular unit may be set into motion. As hereinbefore described, the disk 56 rotates in a clockwise direction (Fig. 3) and, in so doing, causes a winding of the spring 72 until the amount of tension introduced therein is sufficient to start rotation of the disk 67 which, in turn, drives the take-up spool 14 through the frictional contact of the friction pad 66 with the bottom surface of the member 62 and the upper surface of the disk 67. The construction of the spring is such that the disk 56 makes approximately one-half of a revolution before the disk 67 and take-up spool 14 start to rotate. This, of course, depends upon the tension on the strand and the weight of the spool, the latter of which varies as the spool is built up.

During the operation of the apparatus, the strand is constantly maintained under a substantially uniform tension due to the elasticity of the spring 72 which serves to compensate for or take up any irregularities in the tension on the strand being reeled, whether such irregularities be increases or decreases in the tension on the strand. Assuming first, that during the operation of the apparatus, the tension on the strand tends to increase, it will be obvious that such tendency is overcome by a winding of the spring 72 which serves to slow down the rotation of the take-up spool, thereby preventing any increase in the tension on the strand. Assuming now that the tension on the strand tends to decrease, it will be obvious that such tendency is overcome by an unwinding of the spring 72 which tends to speed up the rotation of the take-up spool, thereby preventing any decrease in the tension on the strand. Thus, the tension on the strand is maintained substantially uniform throughout the operation of the apparatus.

Referring to Fig. 1, it is apparent as the distributing roller 44 moves downwardly from the position shown in full outline to the position shown in dotted outline, that the traveling path of the strand between the capstan and the take-up spool gradually decreases and that this path gradually increases when the distributing roller moves in the opposite direction. Therefore, as the distributing roller moves downwardly from the position shown in full outline to the position shown in dotted outline, it is obvious that a certain amount of slack is introduced in that portion of the strand extending from the capstan to the take-up spool. This slack is taken up by an unwinding of the spring 72 which tends to rotate the spool in a direction to wind the surplus material. Assuming now

that the distributing roller is traveling in the opposite direction, that is, from the position shown in dotted outline to the position shown in full outline, it is apparent that the tension on the strand tends to increase since the traveling path of the strand is increasing. This tendency is overcome by a winding of the spring 72 which tends to rotate the take-up spool in a direction to pay off sufficient material to compensate for the increasing length of the traveling path of the material. It should be understood that the above described condition is present whether the capstan is at rest or in motion. The strand is thus constantly maintained under a substantially uniform tension.

Although the invention is herein illustrated and described in connection with a multiple unit tinsel serving apparatus, it should be understood that the novel features thereof are capable of various other applications within the scope of the appended claims.

What is claimed is:

1. In a strand reeling apparatus, a vertically mounted take-up spool, a friction disk for driving said spool, means for driving said friction disk, a spiral spring interconnecting the friction disk and the driving means, for maintaining the strand under a uniform tension, and means for varying the effectiveness of the spiral spring to vary the tension maintained in the strand.

2. In a strand reeling apparatus, a vertically mounted take-up spool, a friction disk for driving said spool, an annular friction pad interposed between the spool and said friction disk, means for driving the friction disk, a spiral spring interconnecting the friction disk and said driving means, and means for varying the maximum tension introduced in said spring.

3. In a strand reeling apparatus, a plurality of take-up spools, a multiple distributor for serving strands upon said take-up spools, individual means for driving said spools, resilient means interconnecting the driving means and the spools for maintaining the strands being reeled under a uniform tension, and means for varying the effectiveness of the resilient means to vary the tension maintained in the strand.

4. In a strand reeling apparatus, a friction disk, a take-up spool mounted thereon, a second friction disk, an annular friction pad interposed between the two friction disks, means for driving the second mentioned friction disk, and resilient means interconnecting the driving means and the second mentioned friction disk for maintaining the strands being reeled under uniform tension.

5. In a strand reeling apparatus, a take-up spool, means for driving said take-up spool, and means comprising a resilient means and

frictional means for effecting a slipping engagement between the resilient means and the take-up spool interconnecting the take-up spool and the driving means for controlling the rotating speed of the spool whereby the strand being reeled is maintained under a uniform tension.

6. In a strand reeling apparatus, a vertically disposed drive shaft, a pinion gear carried thereby, a rotatable disk, an internal gear rotatable with said disk and meshing with said pinion, a take-up spool supported by said disk and resilient means interconnecting the disk and the take-up spool for controlling the rotating speed of the spool to maintain the strand being reeled under a uniform tension.

7. In a strand reeling apparatus, a carrier, a take-up spool mounted thereon, a frictional contact member for driving said carrier, an annular friction pad interposed between said carrier and said frictional contact member, means for driving said friction contact member, resilient means interconnecting the frictional contact member and the means for driving said frictional contact member for maintaining the strand being reeled under uniform tension, said carrier being adapted to enclose the frictional contact member, the friction pad and the resilient means.

8. In a strand reeling apparatus, a vertically disposed drive shaft, a second shaft parallel to the first mentioned shaft, a carrier mounted about the second shaft, a take-up spool positioned upon the carrier, and means actuated by the drive shaft for driving the carrier including resilient means interconnecting the carrier and the drive shaft for controlling the peripheral speed of the spool positioned on the carrier to maintain a uniform tension on the strand being reeled on the take-up spool.

In witness whereof, we hereunto subscribe our names this 16th day of July, A. D. 1926.

DUER CYRUS ROBSON.
